UNITED STATES PATENT OFFICE

140,411

DESIGN FOR AN ENGINE TESTING EQUIPMENT

William H. Yenni and Virgil L. Gunder, Chicago,
Ill., assignors to Joseph Weidenhoff, Inc., a corporation of Illinois

Application February 21, 1944, Serial No. 112,664

Term of patent 14 years

(Cl. D26—1)

To all whom it may concern:

Be it known that we, William H. Yenni and Virgil L. Gunder, citizens of the United States, residing at Chicago, in the county of Cook and State of Illinois, have invented a new, original, and ornamental Design for Engine Testing Equipment, of which the following is a specification:

Figure 1 is a front elevational view of an engine testing equipment in closed position showing my new design;

Figure 2 is a top view of the device as shown in Figure 1;

Figure 3 is an end view of the device as shown in Figure 1; and

Figure 4 is a front elevational view with the movable panels of the device open and in the position of use.

We claim:

The ornamental design for an engine testing equipment, as shown.

WILLIAM H. YENNI.
VIRGIL L. GUENDER.
